UNITED STATES PATENT OFFICE.

WILLIAM J. LEWIS, OF FLINT, MICHIGAN.

DESIGN FOR A HAT-FASTENER.

47,853.

Specification for Design. Patented Sept. 21, 1915.

Application filed April 30, 1915. Serial No. 25,072. Term of patent 14 years.

To all whom it may concern:

Be it known that I, WILLIAM J. LEWIS, a citizen of the United States, residing at Flint, in the county of Genesee and State of Michigan, have invented a new, original, and ornamental Design for Hat-Fasteners, of which the following is a specification, reference being had to the accompanying drawing, forming a part thereof.

Figure 1 is an elevation of a hat fastener,

showing my new design; Fig. 2 is a rear view; and Fig. 3 is an end view.

I claim:

The ornamental design for a hat fastener, as shown.

WILLIAM J. LEWIS.

Witnesses:

JOHN F. BAKER,

JOHN LEWIS.
